UNITED STATES PATENT OFFICE.

FRANK E. HARDING, OF LAWRENCE, MASSACHUSETTS, ASSIGNEE TO ARLINGTON MILLS, OF LAWRENCE, MASSACHUSETTS, A CORPORATION OF MASSACHUSETTS.

SLUB CATCHER AND TENSION FOR DOUBLING MACHINES.

Application filed June 4, 1925. Serial No. 34,846.

The present invention relates to an improvement in doubling machines.

The object of the invention is to produce a tension and slub catcher for use on doublers which will prevent the passing of slubs to the cheese and thereby reduce the amount of mending required in the woven cloth. In doubling machines yarns from two or more bobbins supported in an inclined position in 10 the machine are drawn upwardly through a tension device, then around a drop wire, whence they pass to a guide roll, from which the two yarns pass to the winding mechanism where the double yarn is wound on the cheese. Ordinarily doublers draw yarns from two bobbins, and when one of the yarns breaks or becomes exhausted the drop wire stops the wind, and the operative is required to piece the end. So far as I am aware, no 20 construction of slub catcher has been found adapted to commercial use on doublers for woolen yarn. Consequently occasionally a slub caught on a yarn runs along and is carried through the doubling process and wound up on the cheese. When this yarn is woven, if the weaver does not happen to catch the slub and remove it, the slub is woven into the cloth and such cloth is required to be mended; that is to say, the tedious operation of removing the slub from the woven cloth is required to be performed, and the mending of cloth in a large mill is a very large and serious expense.

The present invention consists in the tension and doubler hereinafter described and particularly defined in the claim; it also consists in the slub catcher itself and, as such, is adapted for use in various machinery.

In the accompanying drawing illustrating the preferred form of the invention, Fig. 1 is a transverse sectional elevation of a portion of a doubling machine; Fig. 2 is a plan view of the parts illustrated in Fig. 1; Fig. 3 is a rear elevation of the tension and slub catcher; and Fig. 4 is a front elevation of the same.

The illustrated embodiment of the invention is described as follows: The yarn 1 from the bobbin moves upwardly to the guide groove 2, thence across the upper surface of the plate 3, under the tension 4, through the slub catcher indicated in a general way by the reference character 5, and thence under the drop wire 6, from which it 55 passes upwardly to the guide roll which re-

ceives this yarn and another yarn from another bobbin where the two yarns run together and form a double strand yarn which is wound on the cheese by the winding mechanism. The guide groove is formed on the 60 front of the plate 3, the upper surface 7 of which forms one member of the tension device. One side of the guide groove is formed by the horn 8 which projects forwardly and upwardly from the plate 3. The other side 65 of the guide groove is formed by the horn 9 which projects diagonally outward and then laterally, as shown in Fig. 2. These horns 8 and 9 provide large guiding surfaces by which the operative may introduce the yarn 70 easily and conveniently into the guide groove without necessitating precise presentation of the yarn thereto. The tension plate 3 is provided on its under side with an ear 10 having a longitudinal hole therethrough to receive 75 the tension supporting rod 11 to which it is secured by means of the set screw 12. A stud 13 is supported in the plate, being received in a boss 14 with a drive fit and projecting upwardly from the plate 3. The 80 lower end of the stud 13 is of reduced diameter. Next above the plate the stud is slightly enlarged in diameter, as at 15 (see Fig. 1). The tension 4, which consists of a small dish-shaped disk having a central hole 85 larger in diameter than the enlarged portion 15 of the stud, rests on the plate 3 or on the yarn, which latter rests on the plate, and the weight of the tension is such as to cause the proper drag to be exerted upon the 90 thread as it passes under the tension. The central hole in the tension being somewhat larger than the enlarged portion 15 of the stud, the tension is permitted to turn freely on the stud with the yarn as it passes under 95 it and to adapt itself to the inequalities of the yarn and yet rotate freely on the stud. Above this enlarged portion 15 of the stud the stud is again reduced in diameter and receives the hub 17 of the threading guide 100 18. The hub 17 is secured in place by means of the set screw 19. The threading guide consists of a shield-like device which (see Fig. 4) extends outwardly from the hub and then downwardly toward the surface of 105 the plate 3. The function of this threading guide is to compel the operator to depress the thread against the upper surface 7 of the plate 3 after laying it in the guide groove 2. This secures the certainty of causing the 110

thread to pass under the tension. In the absence of the threading guide the device would operate as well as in its presence so long as it was operating, but the large side 5 surface 20 of the thread guide affords a larger area against which the thread may be laid in the process of threading up the device than is provided by the upturned lip of the tension. Consequently the threading of 10 the device is greatly facilitated. The slab catcher consists of two parts. The lower part 21 is extended laterally from the ear 10 to the right (see Fig. 4) and is provided at its upper edge with a straight surface 22 15 which forms the lower face of the slab catching groove. The right-hand end 23 of the lower member 21 of the slab catcher is thickened (see Fig. 2) to provide for attachment of the upper slab catching member 24 there- 20 to. The upper slab catching member 24 has a similarly thickened end 25, which corresponds in shape to the thickened end 23 of the lower slab catching member, and a screw 26 screwed into the end 23 of the lower slab 25 catching member affords means for holding the upper member 24 in place on the lower slab catching member 21. Both members are recessed, as shown at 27, to receive the spring 28 which acts to hold the upper slab catching 30 member 24 in as high a position as is permitted by the screw. Two dowel pins 29 and 30 secured in the upper slab catching member 24 are received in dowel holes 31 and 32 in the lower slab catching member and 35 serve to hold the upper slab catching member 24 in correct position in relation to the lower member. The screw is provided with a hex-hole 33 adapted to receive a hex-wrench for use in turning the screw up and down to 40 adjust the positions of the two slab catching members with relation to each other. The upper slab catching member 24 is provided on its lower edge with a slab catching surface 34, between which surface and the sur- 45 face 22 of the lower slab catching member 21 the yarn passes away from the tension and slab catcher to the drop wire. At the inner end of the slot formed between the surfaces 34 and 22 there is provided a slab 50 clearer groove 35 through which slubs may be removed when caught by the catcher. The operative is provided with a thin piece of metal which may be used to push the slab inwardly through the slab catching groove 55 into the slab clearer groove 35. By adjusting the screw 26 the width of the slab catching groove may be regulated to the number of the yarn passing through the device. The upturned end 36 of the upper member 24 of 60 the slab catcher provides a convenient surface along which the yarn being threaded through the device may slide into the slab catching groove.

The operative in threading up the tension 65 and slab catcher presents the thread between

the horns 8 and 9 so that it enters the guide groove. The hand is then moved to the left so that the thread will engage the outer face of the threading guide for the tension; then the hand moves rearwardly so that the thread strikes the inclined end of the upper member of the slab catcher. This inclined end causes the thread as soon as it begins to move to slide down the outer surface of the thread guide for the tension. The operative then 70 passes the thread around the eye 37 of the drop wire and stops the winding mechanism. It is to be observed that the threading guide is supported with its lower edge in fixed and unadjusted position with respect to the upper surface 7 of the tension plate 3. This distance is determined by the shoulder at the lower end of the reduced top portion of the stud 15 so that the device is easily assembled and held in fixed position irrespective of changes in yarn numbers being 75 doubled. When the yarn draws a slab through the device it passes under the tension and thence to the slab catcher which arrests it. This causes the thread to be 80 broken, which in turn permits the drop wire to fall and stops the winding mechanism. The operative, as soon as is convenient, removes the slab from the slab catcher groove and pieces the yarn. This is done by running forward on the "single" running to the cheese, unwinding it from the cheese until the double portion is reached, taking the broken down end therefrom and tying it to the end which was broken at the slab 85 catcher, after which the pieced end is threaded, as has been described. The threading guide for the tension, it is to be observed, affords a convenient means for guiding the thread under the tension, but it also contributes to the threading up of the slab catcher, and so it may be used if desired without the tension in cases where the tension is not necessary.

While the invention is particularly intended and adapted for use on doublers, it is to be understood that it may be employed in winding machines.

Having thus described the invention, what is claimed is:

A tension and slab catcher for doubling machines comprising a tension plate provided with an integral perforated ear to receive a supporting rod and with a vertical stud hole, a stud having a reduced diameter lower end supported in the stud hole in the plate with its shoulder engaging the upper surface of the plate and also having an upper end of reduced diameter, a dish-shaped tension disk having a hole in its center somewhat larger than that of the unreduced portion of the stud and supported thereon, a threading guide having a hub supported on and fitting the reduced upper end of the stud and having a shield portion extending out- 110 115 120 125 130

wardly from the hub beyond the periphery of the tension disk and then downwardly toward the surface of the tension plate, the space between the lower edge of the shield and the plate being fixed by the shoulder on the stud, the tension plate being provided with two forwardly extended horns, one extending forwardly and upwardly from the plate and the other extending forwardly and at a sharp angle to the first horn to form a thread guiding groove and then outwardly and laterally at an obtuse angle to its first direction, thus forming an angular horn, its two portions forming with the first horn a narrow groove and a wide mouth leading to

the groove, and a slab catcher consisting of two jaws of which the lower is formed integrally with the ear of the tension plate and the upper consists of a separate member carrying two dowel pins projecting into two holes in the lower jaw to maintain it in correct position with relation thereto, the jaws being provided with opposed spring recesses, a spring in the recesses normally tending to hold the jaws apart, and a screw to adjust the position of the upper jaw with relation to the lower one. 20 25

In testimony whereof I have signed my name to this specification.

FRANK E. HARDING.
